UNITED STATES PATENT OFFICE.

LLOYD S. HENWOOD, OF LANCASTER, PENNSYLVANIA, ASSIGNOR TO THE NATIONAL STORE SPECIALTY CO., OF LANCASTER, PENNSYLVANIA, A CORPORATION OF PENNSYLVANIA.

LIQUID-DISPENSING TANK.

Application filed May 20, 1926. Serial No. 110,549.

My invention relates to liquid dispensing tanks, and its principal object is to provide means for adjusting and locking the usual overflow pipe in predetermined positions.

5 The invention also contemplates a latch for latching the overflow pipe in positions where its upper end will coincide with graduations on the elevated visible container which includes a yieldable latch which also 10 serves as an adjusting handle for the overflow pipe.

With the preceding and other objects and advantages in mind, the invention consists of the novel constructions, arrangement of 15 parts, and operations to be hereinafter specifically referred to, claimed and illustrated in the accompanying drawing, wherein,

20 Figure 1 is a view partly in elevation and partly in section of a liquid dispensing tank constructed in accordance with my invention.

25 Figure 2 is a fragmentary detailed view showing the lock in locking position, the dotted outline indicating the device in the act of being adjusted.

Referring to the drawing in detail wherein corresponding characters of reference denote corresponding parts throughout the several views, numeral 5 designates the 30 usual graduated visible gasoline or other liquid container supported upon a vertical casing 6. Liquid is supplied to the container 5 in any well known manner. A conventional pump and operating means is designated at 8. Vertically movable through the bottom of the container 5 and through a stuffing box 9 depending from the container is an overflow pipe 10, whose upper end is adapted to coincide with the graduations on the container 5 as shown in Figure 35 1. This overflow pipe 10 is vertically adjustable in a fixed pipe section 11, the latter being secured to a transverse partition 12 in the casing 6, and is provided with a stuffing box or backing 13 at its upper end.

A pair of tubular supports 14 extend vertically within the casing 6, and detachably secured to the upper ends of these supports 14 is a cross-head 15. Formed with the 35 cross-head 15 at its center and depending therefrom is a pair of parallel bars 16, the latter being disposed upon opposite sides of the overflow pipe 10. One of these bars 16

is longer than the other, and has its lower end formed with a horizontal arm or bracket 18, the latter extending across the overflow pipe 10 and detachably connected with one of the supports 14 as indicated at 19. A plurality of pairs of transversely alined spaced plates 21 are secured to the outer faces of the bars 16, each pair of which is provided with coinciding semicircular recesses 22, the arrangement of the plates 21 affording a vertical slot or guide 23 between the inner vertical edges of the plates, and as shown the plates carried by the longer bar 16 are consecutively numbered to coincide with the graduations of the visible container 5. A collar 24 is fixed to the drain pipe 10, and extending laterally therefrom and projecting through the slot 23 is a stem or shank 25 terminating in a circular head 26. A combined adjusting handle and latch for the overflow pipe 10 is designated at 27. This member 27 is hollow and is provided with an opening 28 in its forward end through which the stem 25 projects. The forward end of the member 27 is rounded as indicated at 29, and is adapted to engage in the coinciding semi-circular recesses 22 as shown in Figure 2. An expandible coil spring 30 encircles the stem 25 and has one end positioned against the head 26 and its opposite end bearing against the end wall of the hollow handle and latch 27. An annular finger 35 engaging flange 31 is formed upon the outer end of the member 27.

From the disclosure it will be apparent that upon the operator engaging his fingers with the flange 31, the member 27 may be 40 pulled outwardly to disengage the rounded end 29 from the notches, whereupon the overflow pipe 10 may be adjusted vertically to position its upper end in registration with any one of the graduations on the visible 45 container 5 by moving the member 27 in the required vertical direction. Upon release of this member 27 it will be projected into the predetermined coinciding recesses through the influence of the spring 30, and thereby 50 positively lock the overflow pipe in the desired position.

While I have illustrated and described one embodiment of the invention, I wish to emphasize that I do not limit myself to the 55 exact construction set forth, but that I may

make alterations and modifications therein, and such alterations and modifications are only governed by the appended claims.

What I claim is:—

- 5 1. The combination with an elevated liquid container and a vertically adjustable overflow pipe movable therein, of a rigid element carried by the overflow pipe and projecting laterally therefrom, a spring urged element associated with the rigid element and slidably received on the latter, and graduated means arranged parallel to the overflow pipe and adapted to be engaged by the spring urged manipulating and latching element whereby to hold the overflow pipe in any predetermined position.
- 10 2. Means for adjusting and latching an overflow pipe of a liquid dispensing apparatus comprising a spring urged slidable handle and latch element carried by the overflow pipe, and a plurality of pairs of spaced
- 15
- 20

plates supported adjacent the overflow pipe and extending parallel thereto, and spaced at their inner longitudinal edges to receive the handle and latch element, such plates being provided with coinciding recesses which slidably receive the latch element when the overflow pipe is in set position.

3. The combination with a liquid dispensing apparatus including a vertically adjustable overflow pipe, of a pair of parallel bars supported upon opposite sides of the overflow pipe, pairs of transversely aligned plates secured to the bars and arranged to afford a longitudinal passage-way therebetween, a stem projecting from the overflow pipe and movable vertically in the passage-way, and a spring urged element carried by the stem and adapted to engage the aligned plates.

In testimony whereof I affix my signature.

LLOYD S. HENWOOD.
